UNITED STATES PATENT OFFICE.

WARREN W. BRIGGS, OF PROVIDENCE, RHODE ISLAND, ASSIGNOR TO S. & B. LEDERER, OF SAME PLACE.

DESIGN FOR AN ORNAMENTAL CHAIN.

SPECIFICATION forming part of Design No. 13,715, dated March 13, 1883.

Application filed January 2, 1883. Term of patent 7 years.

To all whom it may concern:

Be it known that I, WARREN W. BRIGGS, a citizen of the United States, residing at Providence, in the county of Providence and State 5 of Rhode Island, have invented and produced a new and original Design for Ornamental Chains, of which the following is a specification, reference being had to the accompanying drawings, forming part thereof.

Figure 1 is a perspective view of two of my newly-designed ornamental chain-links secured together to form a chain. Fig. 2 is a view of one link. Fig. 3 is a perspective view of two of my newly-designed ornamental chain-links, showing a modification of the design. Fig. 4 is a view of one of the links. Fig. 5 is modified form of link.

The leading feature of my design consists in surrounding two, three, or more loops by a 20 sleeve or band either at one end or in the center of the loops, and spreading the other end, or, when the sleeve or band is in the center, both ends apart, to form fan-shaped links.

In the drawings, *a a* are the loops; *b* is a 25 sleeve or band surrounding the loops and holding the same close together. In the drawings the bands are shown as placed on one end of the link, the other end having the loops spread

apart by inserting the rings *c c* between the loops; but the band *b* may be placed in the 30 center of the loops and both ends may be spread apart by the rings *c c*.

d d are rings inserted in the ends of the loops *a a*, and *e* is a connecting-link by which the links are united into a chain. The form of the 35 sleeve or band *b* may be varied to suit the taste.

Having thus described my newly-invented design, I claim as new and desire to secure by Letters Patent—

1. The design for an ornamental chain here- 40 in shown and described, the same consisting of links in which two or more loops are surrounded by a sleeve or band, the loops being close together at the band and spread apart radially and connected together by rings to 45 form a chain, as described.

2. The design for a chain-link, the same con- 50 sisting in two or more loops, *a a*, surrounded by the band *b*, the loops being close together at the band and spread apart radially from the band outward, as described.

WARREN W. BRIGGS.
